US0D1050126S

(12) **United States Design Patent** (10) **Patent No.:** **US D1,050,126 S**
(45) **Date of Patent:** **** Nov. 5, 2024**

(54) **KEYBOARD**

(71) Applicant: **ArithmeType LLC**, North Oaks, MN (US)

(72) Inventors: **Shannon Canas**, North Oaks, MN (US); **Shawn McClintock**, Dazey, ND (US)

(73) Assignee: **ArithmeType LLC**, North Oaks, MN (US)

(**) Term: **15 Years**

(21) Appl. No.: **29/872,271**

(22) Filed: **Mar. 9, 2023**

(51) **LOC (14) Cl.** **14-02**

(52) **U.S. Cl.** USPC **D14/399**

(58) **Field of Classification Search**

USPC D14/388, 393, 399, 391, 455, 496, 247; D16/237
CPC B41J 5/00; B41J 5/10; B41J 5/12; F16M 11/10; G06F 3/0219; G06F 1/1632; G06F 3/02

(57) **CLAIM**

The ornamental design for a keyboard as shown and described.

DESCRIPTION

FIG. 1 is a front perspective view of a keyboard.

FIG. 2 is a top view of the keyboard depicted in FIG. 1.

FIG. 3 is a bottom view of the keyboard depicted in FIG. 1.

FIG. 4 is a front view of the keyboard depicted in FIG. 1.

FIG. 5 is a rear view of the keyboard depicted in FIG. 1.

FIG. 6 is a left side view of the keyboard depicted in FIG. 1; and,

FIG. 7 is a right side view of the keyboard depicted in FIG. 1.

The broken lines in the drawings illustrate portions of the keyboard that form no part of the claimed design.

1 Claim, 5 Drawing Sheets
